ATTACHMENT FOR TELEPHONES

Emanuel Mancuso, Burbank, Calif.

Application June 9, 1958, Serial No. 51,254

Term of patent 14 years

(Cl. D26—14)

Fig. 1 is a perspective view of an attachment for telephones showing my new design;

Fig. 2 is a side elevation thereof;

Fig. 3 is a top plan view thereof, and

Fig. 4 is an end elevation thereof, from the left of Fig. 3.

The fragmentary portion of a telephone desk stand, handset, and pencil shown in broken lines in Fig. 2 are for illustrative purposes only.

I claim:

The ornamental design for an attachment for telephones, as shown and described.
